UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

STENCILING MATERIAL.

1,094,837.

Specification of Letters Patent. Patented Apr. 28, 1914.

No Drawing.

Application filed May 3, 1913. Serial No. 765,236.

To all whom it may concern:

Be it known that I, ALBERT B. DICK, a citizen of the United States, residing at Lake Forest, in the county of Lake and State 5 of Illinois, have invented certain new and useful Improvements in Stenciling Material, of which the following is a specification.

The invention relates more particularly to the use of stencil-sheets which require for 10 their efficient operation moistening as a preliminary to the striking of the type thereon. Stencil-sheets of this character are now being made with a base of open porous paper such as Japanese yoshino paper, this 15 being impregnated with a compound consisting largely of coagulated protein. This compound is normally dry but hygroscopic, and while a stencil may be formed by causing the type of a writing-machine to impinge 20 thereon in such state, yet superior results are obtained if prior to the stencil-cutting operation the sheet is suitably moistened. An ideal moistening fluid must have certain 25 characteristics, included among which is the characteristic of being slow-drying; otherwise, a sheet moistened preliminarily to being placed in a writing-machine would, if the operation were delayed, become dried 30 out before the entire surface thereof had been typed. Again, the fluid should be of such character as to coöperate with the material to which it is preferably applied, in providing a soft backing next adjacent to the stencil-sheet, to avoid fracture of the 35 fibers of the paper, due to the impact of the type.

I have discovered that a highly efficient moistening material may be formed by combining water, glycerin and Turkey-red 40 oil. While the proportions of these may be

varied within wide limits, I prefer to employ a composition consisting of approximately 72% of water, 25% of glycerin, and 3% of Turkey-red oil. These ingredients combine readily in a single solution and may 45 easily be applied to the stencil in any desirable manner, as, for instance, by brushing such solution upon the stencil-sheet itself or by impregnating therewith a sheet of absorbent paper or cloth and placing the same 50 immediately below the stencil-sheet, so that the moisture carried thereby may be readily transmitted to such sheet. As a result of either mode of application, the stencil-sheet is uniformly moistened over the entire operative 55 surface thereof, or so much of such surface as it is desired to utilize in the stencil-cutting operation, and upon the completion of such operation the sheet may be readily dried for insertion in a suitable 60 duplicating machine, adapted for the production of multiple copies.

What I claim and desire to secure by Letters Patent is as follows:—

1. In stenciling material, a stencil-moistening composition including glycerin and Turkey-red oil and a fluid with which said glycerin and oil will combine, substantially as set forth.

2. In stenciling material, a stencil-moistening composition including water, glycerin and Turkey-red oil, substantially as set forth.

This specification signed and witnessed this 28th day of April, 1913.

ALBERT B. DICK.
